APPARATUS FOR DISPENSING SOAP
SOLUTIONS

Ray M. Archibald, Chicago, Ill.

Application January 13, 1930. Serial No. 420,343

11 Claims. (Cl. 299—84)

My invention relates to an apparatus for preparing and dispensing soap or cleanser solutions for washing operations, such as employed in automobile cleaning establishments.

5 One of the objects of my invention is to provide an improved apparatus for preparing and dispensing the proper solution from soap or cleanser materials as it is used.

A further object is to provide an improved 10 apparatus to which a source of water supply may be connected and which will automatically dispense a proper or desired solution of soap or cleanser and water by the simple act of withdrawing water from said source.

15 Other objects of my invention will appear hereinafter.

Referring to the accompanying drawings:

Fig. 1 is a central vertical section of a structure embodying the invention;

20 Fig. 2 is an enlarged section on the line 2—2 of Fig. 1;

Fig. 3 is a detail plan section on line 3—3 of Fig. 1;

25 Fig. 4 is a detail plan section on line 4—4 of Fig. 1;

Fig. 5 is a top plan of the structure shown in Figs. 1 and 8;

Fig. 6 is a detail plan section on line 6—6 of Fig. 1;

30 Fig. 7 is a detail view partly in section of the structure used in connection with a wooden drum, the view being taken substantially on line 7—7 of Fig. 6;

Fig. 8 is a sectional view similar to Fig. 1 of 35 a modified structure; and

Fig. 9 is a detail plan section on line 9—9 of Fig. 8.

The drawings illustrate a structure which is especially designed to carry out my improved 40 process of preparing and dispensing soap solution. This structure comprises in general the container A which contains the soap, and the mixing device B which dispenses the properly proportioned mixture or solution of soap and water.

45 My invention is especially, though not necessarily, adapted for use in garages and washing establishments for washing automobiles, and the soap which is used in these establishments is generally shipped in metal drums or wooden barrels. The container A, although shown relatively small in proportion in the drawings, is intended to be representative of the standard drum or barrel used for this purpose. For this reason, I have constructed the mixing head B, so that 55 it may be utilized in connection with these standard containers.

Drums or barrels usually are provided with a bung-opening in one head 2. In the case of metal 60 drums, the bung opening is defined by an in-

ternally threaded bushing 3 secured in place, while in the case of a wooden barrel simply a round hole 1 is formed in the head thereof.

The structure shown in the drawings is adapted for both types of containers. For metal drums, 65 it has an externally threaded bushing 4 which may be screwed into the bung for mounting the mixing head in place, and which for manufacturing reasons may be a standard reducing bushing. This bushing is attached to the mixing 70 head by being clamped between a shoulder in the bottom annular end member 5 and the end of the cylindrical body member 6 of the mixing and dispensing head.

The mixing and dispensing head is in general 75 made up of the three parts, the bottom end member 5, the body member 6, and the top end member 7. These three parts are assembled together, end to end, and clamped by the clamping bolts 7', Figs. 1, 6, and 8, the top and bottom end 80 members being provided with outstanding flanges 9 and 8, respectively, having suitable holes for the bolts. This construction is desirable from the manufacturing and assembling standpoints and from the standpoint of making the body 85 member interchangeable with a body of the type shown in Fig. 8, hereinafter described. The rest of the parts may be the same for both types.

The bushing 4 has a large opening 10 which forms communication with the interior of the 90 container at the top thereof. The body member is divided into two chambers or passages 11 and 12 by the upright partition wall 13, Fig. 4. These two chambers are separated from each other at their lower ends by the horizontal partition wall 95 14 which has a port or opening 15, a boss being formed on the partition wall into which the upper end of a long extension pipe or tube 16 is mounted.

The partition wall 13 is arc-shaped at its central portion 13', so as to curve around the port opening 15. The threaded boss on the partition wall 14 and the tubular member 16 are less in diameter than the opening 10 in the bushing and are spaced therefrom to afford direct communication between the chamber 11 and the opening 10.

The top end member 7 of the housing has a valve chamber 17 which is connected to a source of water under pressure by means of the inlet pipe 18. A valve or faucet 19 is interposed in this pipe to control the flow of water therethrough and may be of any suitable or standard type by which the flow of water may be turned on or shut off, as desired.

The valve chamber 17 is separated from the two chambers or passages 11 and 12 of the body member by means of a removable partition wall 20 which is preferably in the form of a disc clamped between the end of the body member and a suit-

100

105

110

115

120

- able annular shoulder in the top end member. Gaskets 21 of any suitable type are provided to close this joint. The partition wall 20 is preferably flat and machined smooth on its upper side to form a seat for the disc valve 22. It has two arc-shaped openings or ports 23 which provide communication between the valve chamber 17 and each of the chambers or passages 11 and 12 of the body member.
- 10 The disc valve 22 is seated on the upper face of the partition wall 20 and is pinned to a vertical stem 24 which has a bearing at its lower end in the partition wall 20 and at its upper end in a boss 25 in the cap member. This stem 15 extends through the top of the cap member and through a cap plate 26, and its end is then turned downwardly again into a hole in the plate 26, Figs. 1 and 8, to form a connection by which the stem 24 and the valve 22 may be rotated 20 from the outside of the housing. The operating plate 26 has a series of holes 27 which register with a pin 28 beneath the plate on the upper end of the top member of the housing. These holes and the pin serve to hold the valve 25 in any position to which it is rotatably adjusted, and the holes correspond to a series of openings in the disc valve, as hereinafter described. The operating plate 26 is vertically movable on the stem and its down-turned end, so that it may 30 be raised to disengage the pin 28 when it is desired to adjust the valve, and then dropped into engagement with the selected hole. If desired, a suitable lock 29 may be inserted in the loop formed by the bend in the valve stem to 35 prevent the plate 26 from being moved upwardly and disengaged from the pin. This is intended to prevent unauthorized persons from interfering with the adjustment of the valve.
- The valve disc is yieldingly held against its 40 seat by a coiled spring 30 which is positioned between the disc valve and the boss 25 of the top end member, a self-adjusting bib washer 31 being provided between the spring and the boss.
- The disc valve has an arc-shaped series of 45 ports or holes 32 which register with the arc-shaped ports 23 of the partition wall 20 and form communicating passages between the valve chamber 17 and the chambers 11 and 12. The proportion of water from the valve chamber 50 which flows into each of the chambers 11 and 12 through said ports 23 is thus determined by the relative number of ports which are on the respective sides of partition wall 13, Fig. 3.
- By rotating the valve to position the port holes 55 relatively to the two chambers 11 and 12, the flow of water through the two chambers 11 and 12 may be accurately proportioned.
- In the structure shown in Fig. 1, the chamber 60 12 serves as the mixing chamber. The water from the source under pressure flows directly through this chamber 12, mixes with the soap solution coming into said chamber 12 and the mixture passes out through a nozzle 35 on the end of a pipe 36 which forms the outlet for said 65 mixing chamber.
- The tubular extension 16 is preferably long enough to reach practically to the bottom of the barrel or container when the device is in place, and at its lower end it carries a tapered point 70 40 which diverges to a diameter greater than the diameter of the tube, so that the extension may be forced downwardly through the body of the soap in the container and form a well in the mass of soap which will be of greater diameter 75 than the diameter of the tube. This point 40

has a sleeve 41 which fits over the end of the tube and is fastened thereto, and it has laterally disposed ports 42. A tubular screen 43, concentrically disposed with reference to the lower portion of the tubular member, is held in position 80 between the point member 40 and a collar 44 on said tubular member. This screen is of larger diameter than the tubular extension and serves to maintain a space between the tubular member and the wall of the well formed in the mass 85 of soap. The screen, however, permits the water and soap solution to flow therethrough readily, as hereinafter described.

Soap which is used for the purposes for which this invention is especially adapted, is of two 90 kinds, known to the trade as oil soap and powdered cleansers. Oil soap is usually made in the form of a stiff jelly, whereas the cleansers are manufactured in dry powdered form. The oil soap jelly is generally made stiff or solid enough 95 so that the mass thereof will be self-supporting, that is to say, it has no tendency to flow, although the mass is not hard enough to prevent its being displaced or its form changed by the application of force. The structure shown in Fig. 1 is better 100 adapted for use in connection with oil soaps, whereas the structure shown in Fig. 8, herein-after described, is better adapted for use in connection with powdered cleansers. The material is generally shipped in the containers or barrels A which are filled with the mass to within 105 several inches of the head in which the bung opening is provided.

When a container of oil soap is to be put into service, the tubular extension 16 is inserted 110 through the bung opening and then forced vertically downwardly through the mass of soap. The bushing 4 of the mixing head is then screwed in place in the bushing 3 which forms the bung hole. This seals the container, except for the 115 inlet and outlet formed by the passage 10 and the tubular member 16. The forcing of the point 40 of the tubular member forms a well in the mass of soap which extends the length of the 120 tubular member, the wall of which is spaced from the tubular member. The outlet pipe 36 is then 125 temporarily connected directly to the source of water supply under pressure and water is flowed into mixing chamber 12 and downwardly through the tube 16, in a direction opposite to that indicated by the arrows in Fig. 1. This temporary connection is intended to remove any soap which may have clogged in the port 42 or forced itself through the screen 43, and also for the purpose of filling with water the well formed by the point 130 40 and the space between the top of the mass of soap and the head of the container.

After this is accomplished, the water supply is then disconnected from the outlet pipe 36 and is connected to the pipe 18 with the valve 19 135 closed. The water in the container is allowed to stand in contact with the mass of soap for several hours, and during this period the water will dissolve a portion of the soap from the exposed walls or surfaces of the mass of soap. 140 This dissolving process forms a rich solution which is in liquid form and therefore will flow readily. This solution, however, is too rich for washing purposes and would necessarily entail waste if it were so used. In order, therefore, to 145 deliver or dispense a solution having the proper proportion of soap, this rich solution is diluted with additional water in the mixing chamber 12 as follows:

In order to dispense the proper solution from 150

the nozzle 35, the water supply valve 19 is turned on and the water therefrom under pressure flows from the valve chamber 17 through the chambers 11 and 12. That which flows through the chamber or passage 11, enters the container at the top thereof and displaces the equivalent volume of soap solution within the container. The soap solution which is thus displaced is forced through the ports 42 and upwardly through the tubular extension into the mixing chamber where it meets and is mixed with the water which flows directly from the valve chamber 17 into the mixing chamber 12 through the valve ports. Since the valve has been set to determine the proportion of water passing into the mixing chamber, a proper solution will be dispensed at the outlet or nozzle.

This operation is continued so long as the water is permitted to flow through the structure, and as long as there is a rich solution of soap in the container. Thus, the simple act of turning on the valve 19 to draw water from the nozzle automatically operates to add to the water the proper amount of soap to produce the desired solution. The admission of water through the chamber 11 into the top of the container necessarily thins out the solution within the container, but the dissolving operation of the soap from the mass will again take place until the added water has absorbed its quota of soap from the mass. In practice, the solution is drawn off from the nozzle in comparatively small quantities, one or two bucketfuls at intervals, and these intervals are sufficiently long enough to permit the incoming water into the container to dissolve soap accordingly. The result is that the rich solution within the container remains practically constant. In Fig. 1, the mass of soap is indicated as A-1, after the structure has been in use for a time, and part of the mass has been dissolved and dispensed. The liquid solution is indicated as A-2, and the shaded portions A-3 are intended to illustrate the softened surface portion of the mass of soap in contact with the water in the process of dissolving.

In Fig. 1, the bottom partition wall 14 is provided with a small port 14' which directly connects the chambers 11 and 12. This port is provided so that in the event the water supply valve 19 may leak slightly, the leakage water will flow through the chamber 11, through the port 14', and thence into the outlet nozzle, instead of passing into the container and forcing soap solution into the mixing chamber.

In the case of powdered cleansers only a definite percentage will remain in solution in water, and any material in excess of this quantity will precipitate out and settle down by gravity if allowed to stand; hence, the solution which is at the upper portion of the container will remain fairly constant in its proportion of cleanser and water. For this reason, I prefer to take off the solution from the upper portion of the container and introduce the clear water into the lower zone of the container. This is accomplished by the structure shown in Fig. 8, in which the connection of the chambers with the interior of the container is reversed. In this structure, the container 11' forms the mixing chamber and communicates directly with the upper zone of the interior of the container through the port 10, whereas the chamber 12' communicates with the lower zone of the container through the tubular member 16. The mixing chamber 11' is pro-

vided with the outlet pipe 36 to which is connected the nozzle 35.

Thus, when the valve 19 is opened, the water under pressure from the supply is introduced into the bottom portion of the container, through the tubular member 16, displacing the solution from the top portion of the container and forcing it through the opening 10 and into the chamber 11'. Even though the solid material within the container may be agitated to some extent by the incoming water and thus stir additional cleanser into the solution, the excess will settle down, leaving the solution at the upper portion of the container practically constant.

It may be desirable to cause the solution dispensed from the nozzle to form suds as it flows into the bucket. This can be accomplished by introducing air into the solution as it leaves the nozzle, and a simple expedient for this purpose consists, as shown in Fig. 1, in providing the nozzle with an air passage 35' which communicates with the atmosphere at its upper end and with the solution leaving the lower end of the nozzle. Hence, as the solution leaves the nozzle it draws air into itself through the passage 35', and the agitation of the solution falling into the bucket or container causes the formation of suds.

In order to accommodate the structure to wooden barrels or containers in which soap or cleanser materials are often shipped, I provide the bottom end member 5 of the housing with a tapered outer surface 5', Fig. 7, which is adapted to be wedged into the bung opening of the barrel. The flanges of the bottom end member 5 has holes through which ordinary lag screws 5' are inserted and screwed into the wooden head of the barrel to secure the structure firmly in position.

I am aware that changes may be made in the construction, arrangement and operation of parts of my structure without departing from the spirit of the invention, and I hereby reserve the right to make such changes as fairly fall within the scope of the appended claims.

I claim:

1. The combination of a closed container for soap solution, a mixing device having a mixing chamber connected with an outlet of the container for receiving soap solution therefrom, means for directing a flow of water through said mixing chamber for mixing the water and soap solution therein, means for directing a flow of water into said container to force soap solution from the outlet thereof into said mixing chamber, an adjustable valve controlling the flow of water through said mixing chamber and said container for proportioning the flow therethrough, means for locking said valve in its adjustable position, means forming a discharge outlet for said chamber, and means for introducing air to the solution leaving the mixing chamber.

2. The combination of a container for soap solution and a mixing device having a valve chamber connected with a source of water under pressure, and having a mixing chamber and a passage for water, means connecting said mixing chamber and said water passage with the container at different zones therein, a disc valve between said valve chamber and said mixing chamber and passage, and having a plurality of ports for communication with both the mixing chamber and passage and means for adjusting said valve to vary the relative number of ports communicating with the chamber and passage to proportion the flow of

water through said mixing chamber and passage.

3. The combination of a closed container for soap solution, and a mixing device comprising a housing mounted on said container and having a separated chambers, means forming a port for one of said chambers communicating with the container in one zone thereof, a tube connected to the other of said chambers and extending into said container and forming communication of said chamber with the interior of said container, said housing having a water supply chamber connected with a source of water supply under pressure, and common to both of said other chambers, and a rotary disc valve in the housing between said supply chamber and said other chambers for governing the flow of water through each of said other chambers.

4. In a structure of the class described, the combination of a housing having a chamber and two passages, a wall separating said passages from each other, a partition wall connected with said wall and separating said chamber and said passages, said partition wall having a plurality of openings communicating with each of said passages, and an adjustable disc valve on said partition having a plurality of openings adapted for registration with the holes in said partition to regulate the flow of water from the chamber to the passages.

5. In a structure of the class described, the combination of a housing having a chamber and two passages, a wall separating said passages from each other, a partition wall connected with said wall and separating said chamber and said passages, said partition wall having a plurality of openings communicating with each of said passages, an adjustable disc valve on said partition having a plurality of openings adapted for registration with the holes in said partition to regulate the flow of water from the chamber to each of the passages, a spring pressing said disc against the partition wall, and means accessible outside of said housing for adjusting said disc.

6. The combination of a standard commercial drum for soap solution and having an opening in its head, a mixing device mounted on said drum and comprising a housing having two separated chambers, one of which communicates with said drum directly through said opening, a tubular member mounted in said housing and extending through said head opening and communicating at one end with the lower interior of the drum and at the other end with the other of said chambers, a nozzle forming an outlet for one of said chambers, said housing having a valve chamber connected to a source of water under pressure, and separated from both of said chambers by a partition wall, and a valve in said housing mounted on said partition wall and controlling communication from said valve chamber to said separated chambers for regulating the flow of water therethrough.

7. The combination of a drum container having a bung opening in its upper end and containing a mass of soap, a mixing device adapted to be connected with said opening and having a tubular extension and a head on the end of said extension adapted to be inserted through the opening and forced downwardly through the mass of soap to form a well in the soap larger than the tubular extension, said tubular extension having a port at its lower end and forming a conduit for the passage of soap solution, means connecting said device with a source of water supply, and means forming an outlet for said device, and a

valve means in said device for diverting a portion of the flow of water through said outlet and another portion of the water into the upper portion of said drum to force soap solution through the port and upwardly in the extension to the outlet of the device.

8. The combination of a drum container having a bung opening in its upper end and containing a mass of soap, a mixing device adapted to be connected with said opening and having a tubular extension and a head on the end of said extension adapted to be inserted through the opening and forced downwardly through the mass of soap to form a well in the soap larger than the tubular extension, said tubular extension having a port at its lower end and forming a conduit for the passage of soap solution, means connecting said device with a source of water supply, means forming an outlet for said device, a valve means in said device for diverting a portion of the flow of water through said outlet and another portion of the water into the upper portion of said drum to force soap solution through the port and upwardly in the extension to the outlet of the device, and means at the port in the lower end of said extension for preventing the soap from clogging the port.

9. The combination of a suitable drum container containing a mass of soap to be dissolved into a solution of water, a tubular member forming a conduit for soap solution having a port at its end and an enlarged head adapted to be forced downwardly through the mass of soap to form a well in the mass larger than the diameter of the tubular member, means for introducing water into the upper portion of said well into contact with the soap to dissolve the soap and for withdrawing soap solution from the lower portion of said well through the port and upwardly through the tubular member, and means for mixing additional water with the soap solution withdrawn from said tubular member.

10. The combination of a drum container having an opening in its upper end and containing a mass of soap, a tubular member insertible through said opening and downwardly through the mass of soap and having means for forcing the mass of soap away from the tubular member to form a well in the mass surrounding the tubular member, said tubular member having a port communicating with said well, means for introducing water under pressure to the upper portion of said well to force soap solution from the lower portion of the well upwardly through said tubular member, and means connected with the upper portion of said tubular member for mixing additional water with the soap solution.

11. The combination of a drum container having an opening in its upper end and containing a mass of soap, a tubular member insertible through said opening and downwardly through the mass of soap and having means for forcing the mass of soap away from the tubular member to form a well in the mass surrounding the tubular member, said tubular member having a port communicating with said well, means for introducing water under pressure to the upper portion of said well to force soap solution from the lower portion of the well upwardly through said tubular member, means connected with the upper portion of said tubular member for mixing additional water with the soap solution, and a screen device carried by said tubular member to prevent the clogging of the port therein.
